UNITED STATES PATENT OFFICE.

FREDERICK WILLIAM LANCHESTER, OF BIRMINGHAM, ENGLAND.

BALANCING OF RECIPROCATING ENGINES.

Application filed November 18, 1924. Serial No. 750,849.

To all whom it may concern:

Be it known that I, FREDERICK WILLIAM LANCHESTER, a subject of the King of Great Britain and Ireland, and residing at Dyott 5 End, Oxford Road, Moseley, Birmingham, in the county of Warwick, England, have invented certain new and useful Improvements in the Balancing of Reciprocating Engines, of which the following is a specification.

10 The present invention relates to the balancing of reciprocating engines and has for its object to provide an improved mechanical construction embodying the method of neutralizing the octave and if required the 15 higher harmonic components of piston motion by reverse rotating balance weight running at twice or higher multiple of crank shaft speed.

The present invention consists in brief in 20 harmonic balancing mechanism in which one or more pairs of reverse rotating balance weights are employed to neutralize the constitutional want of balancing of a reciprocating engine in a rotor comprising 25 three parts in which the portions carrying the balance weights are mounted independently of the portion by which the rotor is driven.

30 The present invention further consists in the special constructions and means of mounting the rotor and driving mechanism for same as hereinafter described.

The application of the invention is illustrated by the accompanying sheet of drawings which are diagrammatic and in which like figures refer to like parts throughout:—

40 Figure 1 shows in side elevation an arrangement in which the rotors driven by gearing off the crank shaft are adapted to be driven by screw gear teeth cut in the crank shaft journals between cylinders 1 and 2 and 3 and 4 respectively, a five-bearing crank being shown;

45 Figure 2 shows likewise in elevation an arrangement appropriate to an engine in which a three-bearing crank shaft is employed;

50 Figure 3 shows likewise in elevation an alternative in which the crank shaft is of a two-bearing variety and in which the rotors are arranged to be driven by teeth cut in the end journals;

55 Figure 4 is a transverse section of the crank case showing in longitudinal section one of the rotors in which the rotor consists

of three portions, the central or geared portion being carried by an external journal or bearing bored in the crank case itself and in which the end portions constituting the balance weights are carried independently by 60 a transverse pin arranged coaxial with the main rotor journal aforesaid;

Figures 5 and 6 and Figures 7 and 8 show in detail the component parts of the rotor as illustrated in Figure 4.

Referring to the drawings, A¹ is the crank shaft, A² the screw gear teeth cut in the crank shaft journal. B¹ is the central or driven portion of the rotor element carrying gear teeth B² (Figures 4 and 8) adapted to engage with the gear teeth A², and C is the bearing provided in the crank case for carrying the central portion of the rotor B¹. B³, B⁴ are the end portions of the rotor carried on the pin D which is housed in the crank case at E, E. The central portion of the rotor is adapted to drive balance weights B⁵, B⁶, (Figures 4 and 6) the end portions of the rotor being formed with slots B⁷. These slots may be open-ended and formed by milling deep grooves in the ends of the central portion of rotor B¹ as shown or alternatively rectangular holes may be formed by broaching to receive the balance weights.

The balance weights are centered or journaled on pins D and thus do not give rise to radial forces on the central section of the rotor by which they are driven; the latter is also unaffected by any flexure of the pin D due to centrifugal force. Consequently the 90 truth of the driving gear is not disturbed either by elastic yield or by wear.

Having now described my invention, what I claim as new and desire to secure by Letters Patent is:—

1. Harmonic balancing mechanism for a reciprocating engine including a pair of reverse rotating rotor elements each comprising a driven portion and a pair of balance weights driven thereby but mounted independently thereof.

2. Harmonic balancing mechanism as claimed in claim 1, wherein said driven portions of the rotor elements are mounted in 105 journals and wherein said balance weights are mounted upon pins coaxial with the said journals.

3. Harmonic balancing mechanism as claimed in claim 1, wherein said rotor ele- 110

ments are adapted to be driven by gear teeth cut in the crank shaft journals.

4. Harmonic balancing mechanism for a reciprocating engine including a rotor element, journal bearings therefor, driving means between the engine and said rotor element, a pair of balance weights, a member

supporting said balance weights independently of said journal bearings, and driving means between said balance weights and said 10 rotor element proper.

In testimony whereof I have signed my name to this specification.

FREDERICK WILLIAM LANCHESTER.
